UNITED STATES PATENT OFFICE.

HOWARD B. SHERMAN AND FRANK D. MALTBY, OF BATTLE CREEK, MICHIGAN; SAID MALTBY ASSIGNOR TO SAID SHERMAN.

ELECTRICAL CONNECTION FOR SPARK-PLUGS, &c.

1,352,033.

Specification of Letters Patent.

Patented Sept. 7, 1920.

Application filed January 22, 1919. Serial No. 272,487.

To all whom it may concern:
Be it known that we, HOWARD B. SHERMAN and FRANK D. MALTBY, citizens of the United States, residing at Battle Creek, in the county of Calhoun and State of Michigan, have invented certain new and useful Improvements in Electrical Connections for Spark-Plugs, &c.; and we hereby declare that the following is a full, clear, and exact description thereof, reference being had to the accompanying drawings, which form part of this specification.

Our invention relates to means for connecting electrical devices, and has particular reference to means for connecting terminals of electrical conductors to spark plugs, binding posts and the like.

Common methods of connecting terminals to conductors are to pinch a copper terminal onto the bare wire with a pair of pliers; or solder such terminal thereto. The pinching method does not always make a good electrical connection; and soldering is tedious, expensive, and frequently improperly accomplished; and the ordinary owner of an automobile cannot readily make repairs by such methods.

Our invention enables good electrical connection to be made very quickly and easily, as hereinafter explained.

The objects of our invention are to enable the parts of such connectors to be readily applied to the conductor and spark plug or post; and to enable the conductor, or supply wire, to be readily connected with a spark plug, binding post, etc., without requiring any special tools or any special mechanical skill.

In the accompanying drawings we have illustrated one practical embodiment of the invention and will describe the same to enable others skilled in the art to adopt and use the invention; but we do not consider the invention restricted to the particular construction shown, except as parts thereof may be specifically defined in some of the claims.

In the claims we have summarized the novel essentials and novel features of construction and novel combinations of parts for all of which protection is desired.

In said drawings:

Figure 1 is a view of a complete electrical connection between a conductor or supply

wire and a spark-plug; such connection embodying the at present preferred form of the invention.

Fig. 2 is an enlarged sectional view of the terminal connected to the supply wire.

Fig. 3 is an enlarged sectional view of the cap nut and spring connected with the spark plug.

Fig. 4 is a further enlarged top plan view of Fig. 1.

Fig. 5 is a bottom plan view of the electrical connection shown in Fig. 4.

The conductor or supply wire C may be of the usual kind; being shown as a copper wire or cable incased in an insulating covering. The conductor C is usually provided with some kind of a terminal electrically connected with the conductor and adapted to facilitate engagement thereof with the stem of a spark plug, or binding post. The spark plug P may be of any suitable kind, and as shown has a threaded stem or binding post p upon which a nut is usually screwed to clamp the end or terminal of the conductor C thereto.

In our invention the insulating covering of the conductor C can be stripped off the end of the wire, and such bared end is then inserted into one end of a sleeve 1, preferably formed of insulating material. This sleeve (see Fig. 2) has an internal partition 1^a provided with a small aperture for the passage of the bared end of the conductor, which is usually made up of a plurality of fine wires, and the ends of the wires, projecting through the partition 1^a, are bent or turned against the face of the partition and pinched thereagainst by the shank 2^a, of a novel terminal.

This terminal is preferably made of copper or other suitable conductor of electricity, and as shown in Fig. 1 has a threaded shank 2^a and a tongue 2. The terminal shank 2^a is screwed into the threaded end of the sleeve 1, opposite that end into which the conductor C is entered; and the shank 100 seats upon the ends of the conductor wires and not only makes an excellent electrical connection therewith but also unites the wires mechanically to the sleeve by the screw pressure exerted on the ends of the wires 105 against the partition 1^a so the wires cannot be withdrawn from the sleeve.

The tongue 2 of the terminal may be en-

gaged with a member attached to a binding post, or spark plug shank, as hereinafter described.

In the preferred form of construction, 5 shown in Figs. 1 to 5, a cap 3, of brass or other suitable metal, is provided with an internally threaded recess 3^a by which it can be readily engaged with the end of the binding post, or shank *p* of the spark plug, 10 as indicated in the drawings. This cap 3 preferably has a peripheral flange 3^b on its upper end, the underside of which is engaged by the ends 4^b of a spring retainer 4, also preferably made of suitable conducting 15 metal, which extends diametrically across the top of the cap and has its ends 4^b bent under the flange 3^b as shown; (see Figs. 3 and 4). The inner edges of the ends 4^b of the spring are preferably concaved as 20 shown in Fig. 5, so as to fit against the outer side of the cap 3, and these ends 4^b prevent the spring 4 being disengaged from the cap, while permitting it to be turned upon the cap.

25 The retainer 4 has a loop or bend 4^a, preferably at its center, which is adapted to be entered by the tongue 2 of the terminal. Said tongue can be inserted into the loop 4^a and forced between the retainer 4 and cap 3 (as shown in Figs. 1, 3 and 4) 30 and when so inserted it is tightly clamped against the cap 3 by the retainer.

The retainer 4 serves both to electrically unite the tongue 2 to the cap 3, and to also 35 maintain the cap 3 in place on the stem *p* by preventing its rattling loose or unscrewing.

40 As the retainer 4 can swivel or turn around on cap 3 it is possible to shift the retainer so that the tongue 2 can be readily engaged in the loop 4^a no matter at what point of rotation the cap seats on the binding post or stem, or the spark plug seats in the engine cylinder. This prevents breaking or bending of the conductor, as it can 45 always be led straight to the retainer on the cap without bending or cramping the wires as in other devices.

In the construction shown the sleeve can 50 be readily attached to the conductor; the terminal can be readily attached to the sleeve; the cap can be easily connected to a binding post, or shank; and the terminal can be readily engaged with the cap and when engaged therewith will prevent the 55 cap rotating on the post or shank so as to disengage therewith.

The sleeve 1, when made of suitable insulating material acts as an insulated covering protecting the operator from electrical shock in handling the conductor.

60 With these connections, a car owner, if he has spark plug trouble, does not have to take a pair of pliers and unscrew a nut to withdraw the terminal, but can simply 65 take hold of the sleeve 1, or the cable back

of the sleeve and jerk the terminal tongue out of the cap. He can then determine whether there is any spark action between the spark plug and the terminal by wiping the tongue against any part of the spark 70 plug or post that would give electrical connection and show a spark if the parts were in proper condition; and can easily renew the connection or make repairs thereof or substitute new parts, if necessary, without 75 the use of special tools.

What we claim is:

1. In an electrical connection of the character specified, a cap adapted to be engaged with a binding post or shank of an electric 80 device, and having a peripheral flange, a retainer spring having its ends engaged with said flange to secure it on the cap, and having a bent portion adapted to be engaged with a conductor terminal. 85

2. In an electrical connection of the character specified, a cap having an internally threaded socket, for engagement with the threaded binding post or shank of an electrical device; and a spring retainer extending across and attached to said cap and provided with a bent portion forming an eye 90 for engagement with the terminal of a conductor.

3. In an electrical connection of the type 95 specified, a cap adapted to be attached to a binding post and make electrical contact therewith; and a spring retainer plate extending across the upper end of the cap and having a central loop adapted to permit a 100 terminal to be inserted between said plate and cap and to bind the terminal to the cap when so inserted, substantially as described.

4. An electrical connection for spark 105 plugs and the like, comprising a flanged cap adapted to be affixed to a binding post and make electrical contact therewith; and a spring plate extending across the cap and having its ends loosely engaged with the flange thereof and having a central bend to 110 allow a terminal to be inserted between the plate and cap, said spring-binding the terminal to the cap when so inserted; substantially as described.

5. In an electrical connection of the character specified; a cap having a peripheral flange and provided with an internally threaded socket for engagement with the threaded binding post or shank of an electric 120 device, a retainer spring on top of said cap having its ends bent over and loosely engaged with said flange to retain it on the cap, and provided with an eye to permit a conductor terminal to be inserted between the spring and cap, substantially as described. 125

In testimony that we claim the foregoing as our own, we affix our signatures.

HOWARD B. SHERMAN.

FRANK D. MALTBY.
